Primary Examiner — Ian Simmons*Assistant Examiner* — Mark Cavanna(74) *Attorney, Agent, or Firm* — Pepper Hamilton LLP(57) **CLAIM**

The ornamental design for a memorial plaque, as shown and described.

DESCRIPTION

FIG. 1 is a front perspective view of a memorial plaque showing our new design.

FIG. 2 is a front elevation view thereof.

FIG. 3 is a back elevation view thereof.

FIG. 4 is a right side elevation view thereof.

FIG. 5 is a left side elevation view thereof.

FIG. 6 is a top elevation view thereof; and,

FIG. 7 is a bottom elevation view thereof.

The broken lines are included for the purpose of illustrating portions of the memorial plaque that form no part of the claimed design.

1 Claim, 5 Drawing Sheets(56)
